CLAIM

The ornamental design for a solar powered light with motion sensor, as shown and described.

DESCRIPTION

FIG. 1 is a perspective view of a solar powered light with motion sensor showing our new design, a fragmentary building being shown in broken lines for illustrative purposes only;

FIG. 2 is an inverted perspective view of the solar powered light with motion sensor with the solar panel in an alternate position;

FIG. 3 is a top plan view thereof on an enlarged scale;

FIG. 4 is a left side elevational view thereof on an enlarged scale;

FIG. 5 is a bottom plan view thereof on an enlarged scale;

FIG. 6 is a right side elevational view thereof on an enlarged scale;

FIG. 7 is a front elevational view thereof on an enlarged scale; and,

FIG. 8 is a rear elevational view thereof on an enlarged scale.

FIG. 1

FIG. 2

FIG. 7

FIG. 8
